VALVE

Earnest J. Dillman and William E. Cowley, Detroit, Mich., assignors to Detroit Lubricator Company, Detroit, Mich., a corporation of Michigan

Application June 17, 1940, Serial No. 340,866

9 Claims. (Cl. 137—153)

Our invention relates generally to valves, and more particularly to valves which control flow of liquid refrigerant to a refrigerating evaporator.

An object of our invention is to provide a self-aligning valve needle.

Another object of our invention is to provide a valve structure in which the valve needle will retain its alignment with the valve seat upon subsequent withdrawal of the needle from the seat after original alignment.

Another object of our invention is to provide a valve structure which is economical to manufacture and trouble-free in operation.

The invention consists in the improved construction and combination of parts, to be more fully described hereinafter and the novelty of which will be particularly pointed out and distinctly claimed.

In the accompanying drawing, to be taken as a part of this specification, there is fully and clearly illustrated a preferred embodiment of the invention, in which drawing:

Figure 1 is a view in central vertical section of the valve;

Fig. 2 is a view taken along the line 2—2 of Fig. 1, in the direction of the arrows, with the resilient disk removed;

Fig. 3 is an enlarged detail view of the resilient disk of Fig. 1;

Fig. 4 is a partial view in central vertical section of a modified form of the invention;

Fig. 5 is a partial view in central vertical section of another modified form of the invention, and

Fig. 6 is an exploded view of a portion of the valve means of Fig. 5.

Referring to the drawing by characters of reference, and particularly to Fig. 1, the numeral 1 designates generally a valve casing or body member, preferably a metallic casting, having a triangular, narrow neck portion or extension 2 separating the casting 1 into an upper or heat exchange member 3 and a lower or valve casing 4. An upward diverging or flaring flange 4^a extends upward from the extension 2 and surrounds the upper cylindrical end or hub portion 4^b of the casting 1. An open ended cylindrical chamber 5 is located within and opens through the lower end 6 of the valve casing 4. A dished, circular, plate-like member 7, which seats on the upper end of the casting 1, has a central aperture 8 therethrough and an upturned, continuous flange portion 9 extending from its peripheral edge 9^a. The hub portion 4^b is positioned concentrically within the flange 4^a, and at its top end is re-

ceived within and closes the central aperture 8 in a fluid-tight manner, such as by peening, as at 10. The peripheral portion 9^a of the plate-like member 7 is sealed, as by solder, to the flange 4^a and cooperates therewith, and with the hub portion 4^b, to form an annular or doughnut-like chamber 11. The chamber 11 has an inlet passageway 12 within an inlet boss 12^a and opening horizontally through the flange 4^a adjacent the neck 2, and which may be connected to a source of fluid supply. An outlet passageway, generally designated 13, leads from the chamber 11 into the open ended chamber 5, and thence through a laterally extending outlet boss 13^a for connection to a discharge pipe and positioned on the opposite side of the neck 2 from the chamber 11. The passageway 13 has its inlet port 13^b opening through the side wall of the hub portion 4^b on the opposite side from passageway 12 so that the fluid must have an extended or circuitous travel through chamber 11. A strainer member 14 surrounds the hub portion 4^b within the chamber 11 and is held in position by an annular rib 15^a on the member 7 and a shoulder 15^b on the flange 4^a, so that it is interposed intermediate the inlet passageway 12 and the outlet passageway 13, and acts to stop any foreign matter which may be entrained in the fluid from entering the passageway 13 and clogging the passageway or valve port 15 through a seat member 16 screw-threaded into the passageway 13 through the upper end wall of and at the entrance to the chamber 5.

The chamber 5 is closed at its open lower end portion by a closure member 17 screw-threaded, as at 18, into the chamber 5 and sealed, as by solder, to the lower end 6 of the casting 1. A bolt-like adjustment member 19 has an externally threaded portion 20 which is received by an internally threaded portion 21 of an aperture 22 which extends centrally through the member 17 and opens into the chamber 5. The adjustment member 19 extends upward from the portion 21 through the aperture 22 toward the chamber 5, and terminates in a cone-shaped portion 23. Fluid flow through the aperture 22 along the member 19 is prevented by means of a packing material 23^a which surrounds the member 19 adjacent the portion 23 and is held under compression between annular washer members 24, 25 which are held against shoulders in the aperture 22. The member 24 is held against its shoulder by the expansive force of the compressed packing material, and the member 25 is held against its shoulder by a peened portion 26. The packing material is preferably such that it is

not affected by the application of heat necessary to solder the adjustment member 19, as at 26^a, to the closure member 17 subsequent to final adjustment thereof as a further means to prevent flow of fluid from the chamber 5 past the adjustment member 19. Downward movement of the member 19 is limited by the engagement of a flange portion 26b, carried by the member 19, with the washer member 25 so that in adjustment the member 19 can not be removed from the closure member 17 and packing material. A tubular valve carrier or housing member 27 having an end wall 28 facing the upper end wall of chamber 5 is guided for reciprocal movement within the chamber 5 and has rigidly secured therein against a downward facing shoulder 28^a thereof, as a press-fit, a flanged annular member 29. The horizontal end flange of member 29 is spaced by the shoulder 28^a from the wall 28 so that it cooperates with the wall 28 to form a pair of spaced abutments or shoulders 30, 31. A second tubular valve carrier member 32 is loosely received within the annular member 29 and has a flange portion 33 located intermediate the spaced abutments 30, 31 and seating on the abutment or flange 31. The bore of the tubular member 32 is screw-threaded to adjustably receive the screw-threaded stem of a valve member 35 having a conical valve end portion 36 engageable with seat member 16 and controlling the port 15. A pair of oppositely positioned upstanding ears 37 on the inner periphery of flange 31 of the annular member 29 extend into edge recesses or apertures 38 in the carrier member flange portion 33 to hold the carrier member 32 against rotation so that the valve member 35 can be rotated relative thereto for screw-threaded adjustment. A laterally movable resilient member 40 comprises a pair of spaced substantially parallel side portions 40a which are in the shape of segments of a circle and which are joined by a downwardly bent trough-like central portion 40b. The resilient member 40 has a central aperture through the portion 40b substantially fitting and receiving the valve member 35 and allowing the portion 40b to engage the upper end wall of the valve carrier member 32 adjacent the valve member 35. The side portions 40a engage the abutment 30 thereby to hold the carrier member flange portion 33 against the abutment 31.

An aperture 41 in the end wall 28 through which the valve member 35 extends is of substantially larger diameter than the valve member 35 and the aperture through the annular member 29 is substantially larger than the tubular portion of carrier member 32 so that the valve member 35 and member 32 are laterally movable and free for guided lateral movement on the abutment 31. In this manner we provide structure which makes it possible for the valve member 35, automatically upon movement to full closed seating position, to align itself with the valve port 15 due to the sliding of the flange portion 33 on the abutment 31 and of the resilient member 40 on the abutment 30. The valve member 35, however, having once been aligned with the port 15, is frictionally held in that position due to the resiliency of the member 40. A helical coil spring 42 is positioned in chamber 5 and has one end extending into the annular space between the member 29 and the tubular portion of carrier member 32, and seating against the horizontal flange of member 29 to hold it against the shoulder 28^a and to continually urge the valve member 35 toward port 15. The other or lower

end of spring 42 seats on an annular flange 43 of an abutment member 44 which has a core-shaped or tapered recess 45 in its underside receiving the cone-shaped adjustment member portion 23 so that the spring 42 is held under compression and against expansive movement.

A diaphragm 50 has its peripheral portion sealed to the plate-like member 7 adjacent the peripheral portion 9^a and carries a pair of reinforcing plates 51, 52, the plate 51 being secured to the underside of the diaphragm 50 adjacent the hub portion 4^b, and the reenforcing plate 52 being secured to the underside of the diaphragm 50 away from the hub portion 4^b. A dished, plate-like cap member 53 has a peripheral, upturned, continuous flange portion 54 which substantially fits and is received within the flange portion 9 and is sealed thereto by suitable means, such as solder. The cap member 53 has a spaced horizontal portion 55 overlying and parallel to the diaphragm 50 and cooperable with a raised shoulder portion 56 of the reenforcing member 52 to limit, by engagement, outward movement of the diaphragm 50. Downward or inward movement of the diaphragm 50 is limited by the engagement of the plate 51 and the end of the hub portion 4^b. A helical coil compression spring 57 is held under compression intermediate a second spaced horizontal portion 58 of the plate-like member 53 overlying and parallel to the diaphragm 50 and the reenforcing member 52. A cone-shaped portion 60 of the cap member 53 connects the spaced portions 55, 58 and cooperates with the spaced portion 58 to form a shoulder which acts as a means for locating the upper end of the coil spring 57. The lower end of the spring 57 surrounds and is held in correct operating position by a raised, offset portion 59 of the member 52. A plurality of thrust members 61 have their upper end portions 62 abutting the underside of the reenforcing member 51 and extend downward therefrom through apertures 62^a in the hub portion 4^b and extension 2 and have their lower ends 63 engaging the upper surface of the end wall 28. The springs 42 and 57 act to maintain the valve carrier member 27 and the reenforcing member 51 continually in engagement with the thrust members 61 so that downward and upward movement of the diaphragm 50 acts respectively to open and close the port 15 to flow of fluid. Adjustment of the relative forces of the springs 42, 57 by the adjustment member 19 determines the fluid pressure necessary on the top of the diaphragm relative to that on the underside of the diaphragm to open the valve port 15 to fluid flow. This adjustment controls what is commonly known as the superheat of the valve.

The diaphragm 50 cooperates with the plate-like member 7 and the hub portion 4^b to form a sealed, pressure responsive, expandible-contractible chamber 65 supplied with fluid pressure from the chamber 5 due to the loose fit of the thrust members 61 in their apertures 62^a. This loose fit acts as a restricted flow orifice and prevents any sudden fluctuation of pressure which may occur within chamber 5 from being immediately transferred to the chamber 65 and cause the valve to chatter. The cap member 53 cooperates with the diaphragm 50 to form a second pressure responsive, expandible-contractible chamber 66 which is separated from chamber 65 by the diaphragm 50. The chamber 66 is communicatively connected to a bulb element 67 through a conduit 68 sealed, as by solder, within a central aperture 69 of the horizontal portion 58. The chamber 66,

bulb 67 and conduit 68 cooperate to form a sealed system 70 which contains a quantity of expansible-contractible, volatile fluid so that the fluid pressure varies within chamber 66 in accordance with the temperature of bulb 67. The quantity of volatile fluid in the system 70 is so proportioned relative to the volume of the system that at temperatures of the bulb 67 substantially greater than the maximum operating temperature of the bulb, the fluid will be in a vapor state and any further increase in temperature of the bulb will cause only a very slight pressure increase in the system 70 due to the effect of the gas laws. This type of charging is better known to those skilled in the art as gas charging. The advantage of this type of charging is that at evaporator and bulb temperatures substantially above the normal operating temperatures the valve acts to supply liquid refrigerant to the evaporator to maintain a substantially constant predetermined evaporator pressure to prevent overloading of the compressor, while at evaporator temperatures and consequently bulb temperatures within the normal operating range of the evaporator, the valve acts to supply liquid refrigerant to the evaporator to maintain liquid refrigerant substantially throughout the entire evaporator for the most efficient operation thereof. The details of this type of operation are well known to those skilled in the art.

It is also well known that in a valve of this type the temperature of the bulb 67 must be maintained as the coldest point in the system 70 so that the pressure within the system is substantially that corresponding to the vapor pressure of the liquid at the temperature of the bulb 67. This temperature is above that of the refrigerant in chamber 5 and in the evaporator, and the chamber 66 must therefore be maintained warmer than the chamber 5 to prevent distillation of the liquid from bulb 67 to the chamber 66, which would render the valve inoperative. In the structure shown and described, we utilize the heat of the incoming liquid refrigerant within the annular chamber 11 to maintain both of the chambers 65, 66 above the temperature corresponding to the vapor pressure of the refrigerant in chamber 5. It is to be noted that we maintain the neck portion or extension 2 of the valve casting 1 connecting the upper and lower portions thereof, and shown in Fig. 4, as small as possible so that a high resistance path to the flow of heat from chambers 65, 66 to chamber 5 is maintained. In this manner we conserve the heat carried to the chamber 11 by the incoming warm liquid as long as possible and prevent the temperature of chamber 66 from assuming evaporator temperature during a long "off" cycle of the refrigerating apparatus. The heat capacity of the exchange member 3, including that of the fluid within the chamber 11, is preferably high in proportion to that of the valve casing 4, and fluid within the chamber 5, to further prevent the cooling of the chambers 65, 66 to the temperatures of the valve casing 4. By utilizing this structure a single diaphragm, gas charged, thermostatic valve can be used in ambient temperatures more closely approaching those of the evaporator than the gas charged valves of the prior art using the conventional double bellows construction without the distillation of the charge from the bulb to the pressure sensitive chamber. By utilizing the heat of the warm liquid flowing to the valve to heat and maintain the chambers 65, 66 above evaporator temperature, the liquid becomes sub-cooled 75

and the refrigerating capacity of the valve structure for a given orifice size is increased. This increased capacity and resultant smoother action is due to the reduction of the volatilization of the liquid refrigerant necessary to bring the temperature of the incoming liquid refrigerant down to the evaporating temperature of the refrigerant in the evaporator upon passage through the port 15.

10 Fig. 4 shows a modification of the apparatus of Fig. 1 and in which like parts are designated by like numerals with the exponent *d* added. The lower end of the chamber 5^d is closed by means of a cap member 75 which is screw-threaded thereinto, as at 76. The inner end of the cap member 75 has a recess 77 which receives and limits outward movement of the lower abutment member 44^d under influence of the spring 42^d. Normally the abutment member 44^d is held away from the bottom wall of the recess 77 by means of an adjusting member 78 which is similar to member 19 in that it has a conical portion 79 which is received in the tapered recess 45^d of member 44^d and has a screw-threaded portion 80 which cooperates with a threaded portion of the cap member 75 to position the member longitudinally thereof. Suitable packing material 81 surrounds the stem portion of the adjusting member 78 to prevent leakage along the member 78 from the chamber 5^d. The material 81 is forced in any suitable manner, not shown, against a tapered annular washer member 82 so that the material 81 is maintained in intimate contact with the stem of the member 78. A shoulder 83 on the member 78 is engageable with the washer member 82 to limit outward movement of member 78 so that substantially upon engagement of the abutment member 44^d with the bottom of the recess 77 further outward movement of the member 78 is prevented. The upper end of the spring 42^d engages the underside of an end wall 84 of a tubular valve carrier member 85. The member 85 is guided for reciprocal movement by the inner side walls of the chamber 5^d and is moved by the pressures within the chambers 65 and 66 acting on the diaphragm 50 and through the members 61^d. The end wall 84 has a central aperture therethrough and through which the valve member 35^d and its tubular carrier member 32^d extend, and the flange portion 33^d engages and seats against the top surface of the end wall 84. The flange portion 33^d is resiliently held against the wall 84 by the resilient member 40^d which has its parallel side portions abutting the under face of an annular flanged disk 86 and its trough-like portion abutting the member 32^d. The disk 86 has its flanged portion press-fitted to the circumference of carrier member 85 and is positioned in relative spaced relation to the end wall 84 by engagement of the flanged portion with a shoulder on the carrier member 85. The disk 86 has two lugs 87 bent downwardly therefrom toward the end wall 84 which are aligned with and extend into the edge recesses 38^d of the flange portion 33^d. The lugs 87 and recesses 38^d cooperate similarly to the ears 37 and recesses 38. In the modification of Fig. 4, the thrust members 61^d engage the upper face of the annular disk 86 instead of engaging the top wall of the valve carrier member 85 as in Fig. 1.

In Fig. 5 there is shown a still further modification of the invention in which like parts to other figures are designated by the same numerals with the exponent *c* added. The end wall 23^c of the carrier member 27^c has an upstanding boss

90 surrounding its central aperture and the outer peripheral surface of the boss 90 is rounded, as at 91, to receive an annular disk member 92 whose central aperture receives a portion of the boss 90 so that the disk member 92 seats against the rounded portion 91. The thrust members 61^c abut the upper face of the disk member 92 and transmit motion therethrough to the carrier member 27^c. The member 92 may cant about the boss 90 and any irregularities in the movement of the diaphragm 50 or in the lengths of the thrust members 61^c will not be transmitted to the carrier member 27^c to cause it to stick or bind in its reciprocal movement. The lower end portions of the thrust members 61^c, which are positioned within the chamber 5^c, may have a peripheral recess to receive an endless coil spring 93 which tends to draw the thrust members 61^c radially inward so that they frictionally engage the side walls of the apertures 62^c. A flanged annular member 94 is similar to member 28^c in that it is press-fitted into the interior of the carrier member 27^c against an internal shoulder thereof to form a pair of spaced abutments or shoulders 30^c, 31^c and between which is positioned the flange portion 33^c of the second carrier member 32^c. The portion 33^c is held against shoulder 31^c by the resilient member 40^c which has its parallel side portions engaging shoulder 30^c. A pair of lugs 95 are stamped out of the end wall of the annular member 94 so that they extend into the recesses 38 of the flange portion 33^c and cooperate therewith substantially as the ears 38 cooperate with the recesses 38. Fig. 6 shows in detail the flanged annular member 94 and the valve carrier member 32^c.

The operation of our apparatus is as follows: The valve shown is particularly adapted for use on a refrigerating system in which the liquid supply line is connected to the inlet boss 12^a and the refrigerant evaporator inlet is connected to the outlet boss 13^a in communication with passageways 12, 13 respectively. The bulb 67 is preferably secured in good heat exchange relation with the outlet of the evaporator so that it is sensitive to the temperature of the refrigerant leaving the evaporator. Warm high pressure liquid refrigerant flows from the source of supply into chamber 11 through the strainer member 14 and into passageway 13, giving off heat to maintain the chambers 65, 66 at a temperature above that of the liquid refrigerant in the evaporator and valve casing 4. Flow through the passageway 13 to the boss 13^a is controlled by means of the valve member 35 cooperating with the valve port 15. The fluid pressure within chamber 5 is transmitted to the chamber 65 through the apertures 62^a and increase in pressure within the chamber 65 tends to move the diaphragm 50 outwardly so that the spring 42 is operable to move the valve member 35 into valve closed position. Decrease in temperature of the refrigerant leaving the evaporator is accompanied by a corresponding decrease in temperature of the bulb 67, thereby lowering the pressure within chamber 66 tending to move the valve member 35 to closed position. Decrease in temperature of the refrigerant in the evaporator is accompanied by a decrease in pressure thereof, and consequently in the chamber 65, tending to move the valve member 35 to open position. The springs 42, 57 have their forces so balanced relative to each other, and to the fluid forces in chambers 65, 66 acting on the diaphragm 50, that during normal operation, the valve member 35 will be moved

toward open position when the temperature of the bulb 67 is slightly higher than the evaporating temperature of the refrigerant within the evaporator. The valve member 35 will therefore 5 act to maintain the evaporator substantially filled with evaporating liquid refrigerant during compressor operation, in a manner similar to that of prior art thermostatically operated refrigerant flow controlling valves. Enough heat is stored in the exchange member 3, and resistance to heat flow through the extension 2 is great enough so that during the "off" periods of the refrigerating compressor the chambers 65, 66 are not lowered to the temperature of the valve casing 4. The 10 valve member 35 and its tubular carrier member 27 is frictionally held against the abutment 31 so that upon initial seating of the conical portion 36 against the valve seat member 16 the valve member 35 may move laterally of the carrier member 27 so that it aligns itself with the valve port 15. Upon subsequent operation of the valve member 35 it will maintain itself aligned and in correctly set position so that upon subsequent closing, the valve member 35 is in the correct cooperating position.

The operation of the valve structure of Figs 4, 5 and 6 is substantially the same as that described in relation to Fig. 1 in that the valve member has lateral movement relative to its seat and is resiliently held in adjusted position against a lower shoulder.

It may therefore be seen that the new and novel structure shown and described is a new and improved means for obtaining a self-aligning valve needle and one which is economical and simple of manufacture.

This application is a continuation in part of our copending application Serial No. 271,756, filed May 4, 1939, for valves.

40 What is claimed and desired to be obtained by Letters Patent of the United States is:

1. In a valve of the character described, a casing having a passageway therethrough and including a valve port, a valve carrier member within said casing and having reciprocal movement, said carrier member having an annular shoulder, a valve supporting means laterally movable on and engaging said shoulder, a valve screw-threadedly secured to and extending through said supporting means, means interconnecting said carrier member and said supporting means and operable to prevent rotation of said supporting means relative to said carrier member so that said valve may be rotated in said supporting means for adjustment relative thereto, and resilient means urging said supporting means against said shoulder, said valve being operable upon said reciprocal movement to control flow through said port, said supporting means being movable laterally on said shoulder by the engagement of said valve with the wall of said port thereby to align said valve with said port.

2. In a valve of the character described, a casing having a passageway therethrough and including a valve port, a valve carrier member reciprocal in said casing and having a pair of spaced abutments, one of said abutments facing said port, valve means cooperable with said port for controlling flow of fluid through said passageway and laterally movable on and engaging said one abutment, resilient means interposed between and engaging the other of said abutments and said valve means and being laterally shiftable bodily on said other abutment and

with said valve means for maintaining said valve means in a fixed adjustable lateral position on and in engagement with said one abutment, and means for moving said carrier member toward said port, said valve means upon initial seating engagement with the wall of said port shifting laterally into accurate alinement therewith and bodily shifting said resilient means to hold said valve means in such alinement for all subsequent closing of said port by said valve means.

3. In a valve of the character described, a casing having a passageway therethrough and including a valve port, a valve carrier member reciprocal in said casing and having a pair of spaced abutments, one of said abutments facing said port, a laterally movable valve member cooperable with said port for controlling flow of fluid through said passageway and having a shoulder portion positioned between said spaced abutments and in engagement with said one abutment, and a spring disk member having a central aperture therethrough, said valve member extending through and substantially fitting said central aperture, said disk member being interposed between the other of said abutments and said shoulder portion and being laterally shiftable bodily on said other abutment, said valve member being laterally movable on said one abutment upon initial engagement with said port, said disk member being laterally shifted on said other abutment by the lateral movement of said valve member, said disk member acting in its lateral shifted position to maintain said shoulder portion in engagement with said one abutment and to maintain said valve member in its laterally moved position for all subsequent closing of said port by said valve member.

4. In a valve of the character described, a casing having a passageway therethrough and including a valve port, said casing having a chamber communicating with said passageway, a tubular valve carrier member reciprocal in said chamber and having an end wall, said end wall having a central aperture therethrough, an annular member within and rigid with said tubular member and cooperating with said end wall to form a pair of spaced abutments, a valve member cooperable with said port for controlling flow of fluid through said passageway and having a shoulder portion positioned between said spaced abutments, said valve member extending through and movable relative to said end wall central aperture, and a spring disk member having a central aperture therethrough, said valve member extending through said disk member central aperture, said disk member being interposed between one of said abutments and said shoulder portion and urging said shoulder portion into engagement with the other of said abutments.

5. In a valve of the character described, a casing having a passageway therethrough and including a valve port, said casing having a chamber communicating with said passageway, a tubular valve carrier member reciprocal in said chamber and having an end wall, said end wall having a central aperture therethrough, an annular member within and rigid with said tubular member and cooperating with said end wall to form a pair of spaced abutments, said annular member having a pair of upstanding ears, a valve member cooperable with said port for controlling flow of fluid through said passageway and having a shoulder portion positioned between said spaced abutments, said shoulder por-

tion having a pair of recesses receiving said ears, said valve member extending through and movable relative to said end wall central aperture, and a spring member having a central aperture therethrough, said valve member extending through said spring member central aperture, said spring member being interposed between one of said abutments and said shoulder portion and urging said shoulder portion into engagement with the other of said abutments.

6. In a valve of the character described, a casing having a passageway therethrough and including a valve port, said casing having a chamber communicating with said passageway adjacent said port, a tubular carrier member having an end wall, said end wall having an aperture therethrough, said carrier member having a normal diameter internal portion intermediate its ends and having a reduced diameter internal portion intermediate said end wall and said normal diameter portion, said end wall intermediate said reduced diameter portion and said end wall aperture forming a seating surface, an internal shoulder within said carrier member formed at the intersection of said reduced diameter portion and said normal diameter portion, said carrier member having an enlarged diameter internal portion leading from the end thereof opposite to said end wall to said normal diameter portion, an annular member having a substantially perpendicularly extending side wall, said perpendicular side wall being of less external diameter than said enlarged diameter portion and operable to be press fitted into said normal diameter portion with said annular member positioned against said shoulder, said annular member forming a seating surface facing said first-named seating surface, a valve member extending through said end wall aperture and having a flange portion positioned intermediate said seating surfaces, and means under stress and abutting one of said seating surfaces for holding said flange portion against the other of said seating surfaces.

7. In a valve of the character described, a casing having a passageway therethrough and including a valve port, said casing having a chamber communicating with said passageway adjacent said port, a tubular carrier member reciprocal within said chamber and having an end wall and having a recess providing an annular shoulder adjacent said end wall, an annular member having a substantially perpendicularly extending flange, said flange being operable to be press fitted into said recess, said shoulder acting to limit movement of said annular member toward said end wall, said annular member and said end wall cooperating to provide a pair of spaced abutments, a valve member having a flange positioned intermediate said spaced abutments and having a portion projecting through said annular member and cooperable with said port for controlling flow of fluid there through, and resilient means positioned intermediate said abutments and acting to urge said flange into engagement with one of said abutments.

8. In a valve of the character described, a casing having a passageway therethrough for flow of fluid and including a valve port, said casing having a chamber communicating with said passageway and aligned with said port, a valve carrier member guided for longitudinal reciprocal movement in said chamber toward and away from said port and having a pair of spaced annular abutments, a valve supporting member having a flange, said flange being positioned intermediate

said abutments and having a recess in its peripheral portion, one of said abutments having a finger portion extending into said recess and operable to hold said supporting member against rotation within said carrier member, a valve member screw-threadedly secured within said supporting member and extending beyond the other of said abutments and cooperable with said port for controlling flow of fluid there through, said valve member having a tool receiving portion adjacent the end of said valve member extending away from said port, said valve member being operable to be rotated by said tool portion to adjust said valve member relative to said carrier member.

9. In a valve of the character described, a casing having a passageway therethrough and including a valve port, a valve carrier member reciprocal in said casing and having a pair of spaced abutments, valve means cooperable with 20

said port for controlling flow of fluid through said passageway and laterally movable on and engaging one of said abutments, resilient means interposed between and engaging the other of said abutments and said valve means and being laterally shiftable bodily on said other abutment and with said valve means for maintaining said valve means in a fixed adjustable lateral position on and in engagement with said one abutment, and means for moving said carrier member toward said port, said valve means upon initial seating engagement with the wall of said port shifting laterally into accurate alinement therewith and bodily shifting said resilient means to hold said valve means in such alinement for all subsequent closing of said port by said valve means.
